PISTON RING

Fred D. Durham, Louisville, Ky., assignor to C.
Lee Cook Manufacturing Company, Louisville,
Ky., a corporation of Kentucky

Application June 24, 1935, Serial No. 28,182

1 Claim. (Cl. 309—29)

The present invention relates to piston rings, and the object is to provide a ring made up of cooperating members in which fluid under pressure is admitted behind the ring for the purpose of expanding it and keeping it in proper contact with the cylinder wall, and yet the members are so related that this expansion is limited and the danger of a member being expanded or sprung into a port of the cylinder wall passing the same is reduced to a minimum.

10 In the accompanying drawing:

Figure 1 is a longitudinal sectional view through a portion of an engine cylinder showing a part of the piston therein, and illustrating two 15 of the rings in place, one in elevation and the other in section.

Figure 2 is a perspective view showing the underside of the ring assembly.

Figure 3 is a detail perspective view showing 20 the open passageway between the ends of the upper ring member.

Figure 4 is a detail sectional view illustrating the manner in which the fluid under pressure is admitted behind the ring.

25 Figure 5 is a sectional view showing the joint of the lower ring member sealed against the passage of motive fluid.

In the embodiment disclosed the piston ring consists of an upper ring member 6 and a lower 30 ring member 7 placed face to face. One of these members, as the lower, is provided with a longitudinal tongue 8 on its upper face, and the opposing lower face of the upper member is provided with a corresponding groove 9 that receives 35 the tongue. Both ring members are of spring metal, and are split so that they may expand and contract, and consequently have their ends spaced apart. The space 10 between the ends 11 of the upper member is unobstructed. This 40 member, it being understood, is on the pressure side of the piston. The space 12 between the ends of the lower member is, however, sealed, and for this purpose the upper member is provided with 45 a depending flange 13 which bridges the said space 12. The inner sides of the ends 14 of the lower member 7 are cut away, as shown at 15 to receive the ends of the said flange 13, and consequently slidably lap said flange. As shown the corners 16 of said ends 14 and the corners 17 of 50 the ends 11 are preferably rounded off so that they will not cut or score the cylinder wall.

With this structure, it will be evident that considering the so-called upper ring member as the member which faces the pressure side of the 55 piston, it will be evident by reference to Figure 4 that when pressure is on the piston the fluid which may pass between the piston and cylinder wall, respectively designated A and B can find its way between the ends 11 of the member 6 to 60 the rear or inner side of the piston ring, and

thus expand the ring assembly outwardly against the cylinder wall. On the other hand, the space 12 between the ends 14 of the lower member 7 is sealed by the flange 13 and consequently there can be no escape of this fluid under pressure at 5 this point.

There is a peculiar interrelation in this arrangement with the interlocking of the two members by the tongue and groove formation, in that while expansion of the ring assembly is permitted, there can be no excessive expansion of one of the ring members with respect to the other, and consequently one acts as a resisting member for the other, so that the danger of one ring member being pressed out or expanded or sprung 15 into a port while passing the same, with consequent injury to the parts, is avoided.

It moreover avoids the necessity of the use of dowels for holding the ring members against relative movement. The use of dowels is an 20 expensive item, and it is difficult to secure them in place. Furthermore the action of the ring members frequently shears the dowel, causing cylinder scoring and uneven groove wear.

In the present structure the ring assembly is 25 free to adjust its position in the ring groove, as such adjustment is made necessary by irregularities of the cylinder bore. This freedom of movement not only eliminates uneven groove wear, 30 but has the advantages of allowing the lower ring 35 surface to lap itself into the groove landing, thus providing a more efficient and effective seal.

From the foregoing, it is thought that the construction, operation and many advantages of 35 the herein described invention will be apparent 40 to those skilled in the art without further description, and it will be understood that various changes in the size, shape, proportion and minor details of construction may be resorted to without departing from the spirit or sacrificing any 45 of the advantages of the invention.

What I claim is:—

A piston ring comprising spring ring members, one of which has a longitudinal tongue on one 45 of its side faces, the other having in its opposing face a longitudinal groove to receive the tongue, said ring members being split, one of the ring members having a sealing flange on its inner side that extends across the space between the ends 50 of the other ring member and has said ends slidably upon the end portions of the flange, the space between the ends of said flange carrying member being open to the passage of fluid under pressure therethrough and to the back of the ring 55 assembly, the ends of said rings having rounded outer corners said ring members being relatively rotatable one on the other, and said members being limited in said relative rotation by the sealing flange.

FRED D. DURHAM.
